UNITED STATES PATENT OFFICE.

HERMANN DIEHL, OF FRANKFORT-ON-THE-MAIN-BOCKENHEIM, GERMANY, ASSIGNOR
TO THE FIRM OF MAFAM MOTOR-APPARATE G. M. B. H., OF FRANKFORT-ON-THE-
MAIN, GERMANY.

AUTOMATIC TIMING MECHANISM FOR MAGNETOS.

1,273,044.

Specification of Letters Patent.

Patented July 16, 1918.

Application filed November 9, 1911, Serial No. 659,312. Renewed December 10, 1917. Serial No. 206,546.

To all whom it may concern:

Be it known that I, HERMANN DIEHL, a citizen of the German Empire, residing at Frankfort-on-the-Main-Bockenheim, in the 5 Kingdom of Prussia, Province of Hesse-Nassau, Germany, have invented certain new and useful Improvements in Automatic Timing Mechanism for Magnetos, of which the following is a specification.

10 This invention relates to improved means for use in automatically regulating the "timing" in magneto-ignition apparatus, such as commonly employed in connection with internal combustion engines. Such 15 timing is dependent upon the angular position of the magneto-shaft, whereon the armature is mounted, in relation to that of the motor-shaft, or shaft driven therefrom; and many attempts have been made to vary 20 such angular position automatically upon a change occurring in the speed of the engine.

The majority of the devices hitherto proposed present, however, the disadvantage that, when arranged inside a casing, they 25 entail structural modifications in the magneto; and in other instances where such modifications are not entailed, modifications in the motor casing become necessary.

It has also been proposed to arrange the 30 regulating device as a coupling between the free end of the motor-shaft and that of the magneto-shaft, that is to say, on the end of one shaft centrifugal bodies are pivotally mounted, and, by means of levers, tooth- 35 gearing or the like, engage with corresponding parts connected to the end of the other shaft.

Constructions of this character have the 40 defect that, owing to the manner in which the coupling parts engage the shafts, great accuracy as regards axial alinement is necessary; and they require moreover readjustment whenever the magneto has been removed. As the space in the magneto is very 45 restricted, this operation is usually attended with considerable difficulty. The space occupied in a longitudinal direction constitutes another disadvantage.

The object of the present invention is to 50 provide an apparatus capable of being fitted to the motor-shaft or the magneto-shaft of any make, and even of being readily adapted to any existing machine; the construction

being such that the restricted space available in a longitudinal direction is not seriously 55 encroached upon.

This effect can only be achieved by constructing the regulating device as an independent and self-contained apparatus, wherein the working parts are inclosed and 60 wherein the parts which engage together and are turned relatively to each other are invariably pivoted one in another, so that the timing regulator may be made ready for use and inserted in any machine without requiring the operative parts to be readjusted. In such cases it is sufficient to mount the apparatus concentrically in relation either to the end of the motor driven shaft or to the magneto shaft. 70

In the accompanying drawings, wherein is illustrated the apparatus mounted in the manner last referred to, Figure 1 is a side elevation of a magneto embodying my improved timing regulator the latter appearing in vertical section; and Fig. 2 is an end elevation, the cap having been removed. 75

Referring more particularly to Fig. 1, the timing regulator is carried by the small conical-ended shaft *c*, commonly used in 80 magneto-apparatus; the magneto-shaft being driven indirectly from the motor-shaft *m* by means of claws *k* which engage with projections *n*, or by any other suitable means. It is not essential for the shaft *m* 85 to rotate in accurate alinement with the magneto-shaft *c*; inaccuracy of alinement being compensated for by slight play between the claws *k* and the projections *n*.

Space is economized seeing that the entire 90 apparatus is inclosed within the flat casing *h*. This casing *h* is rotatably mounted on the bearing *l* formed upon the part *z*₁; the latter being formed with a central recess *w* adapted to receive the end *c* of the magneto- 95 shaft.

To produce the advance of the part *z*₁ which is fast upon the shaft *c*, in relation to the casing *h* which is rigidly connected to the motor-shaft *m*, centrifugal bodies *p* are 100 employed which, in the example given, are provided with teeth which mesh, as shown in Fig. 2 with teeth formed upon the part *z*₁ and also with toothed racks arranged upon the interior of the casing *h*. It will be understood that, with the movement of the cen- 105

trifugal bodies p , their toothed portions impart movement both to the central pinion and to the internally toothed surrounding casing thus thereby effecting a larger angular displacement than if the centrifugal bodies p were pivoted on fixed bearings and engaged with a single tooth-gear, as has already been proposed.

The object of the present invention is, 10 however, not limited to the employment of fly-weights or levers as described, as any other kind of fly-levers or any equivalent contrivance may be used to the same effect.

The casing h may also be made and pivoted in any suitable way and it is not required, even though preferable, to arrange the same in the shape of a chamber closed on all sides. It is also irrelevant with respect to the inventive idea whether the casing h is pivoted upon the piece z' , or whether the latter is provided with another recess in which the casing h by means of a hollow shaft may be pivoted. It is important, however, that each of the parts to be turned 25 relatively to each other forms the bearing of the other part.

In cases where the inductor is not driven directly by the motor shaft m but by means of a gearing, the casing h is preferably provided with a tooth-wheel gearing z_2 to engage with directly.

Preferably the part z_2 forms the protecting case of the apparatus but if desired the part z_1 may be easily used for this purpose.

Having now particularly described and ascertained the nature of my said invention and in what manner the same is to be performed, I claim:—

1. In mechanism of the class described, in 40 combination, a motor shaft, a magneto shaft, two connected parts concentrically rotatable relatively to each other, means for attaching one of said parts concentrically to one of said shafts, said parts being so arranged that both of said parts will be intersected by 45 a single plane at right angles to the axis of said one of said shafts and so arranged that each of said parts presents a bearing surface for the other, and connecting means 50 between said two parts which automatically varies their relative angular position de-

pending upon the speed of rotation of said one of said shafts.

2. In mechanism of the class described, in combination, a motor shaft, a magneto shaft, 55 two connecting parts concentrically rotatable relatively to each other and so arranged that one of said parts is loosely sleeved directly upon the other, means for attaching one of said parts concentrically to one of said shafts, and connecting means between 60 said two parts which automatically varies their relative angular position depending upon the speed of rotation of said one of said shafts, one of said two parts constituting a casing inclosing the other part and said connecting means.

3. In mechanism of the class described, in combination, a motor shaft, a magneto shaft, 65 two connecting parts concentrically rotatable relatively to each other and so arranged that one of said parts is loosely sleeved directly upon the other, means for attaching one of said parts concentrically to one of said shafts, and connecting means between 70 said two parts which automatically varies their relative angular position depending upon the speed of rotation of said one of said shafts, said connecting means including 75 an external gear on one of said parts, an internal gear on the other, and a centrifugal body pivoted in one of said parts and bearing a gear adjacent its pivot in intermediate mesh with both of the other gears.

4. In mechanism of the class described, in 80 combination, a motor shaft, a magneto shaft, a hub mounted upon one of said shafts, an external gear on the hub, a hollow member 85 centrifugally and rotatably arranged on said hub and inclosing said external gear, an internal gear within said member concentric with the external gear, and a centrifugal body pivoted in said member and bearing a gear adjacent its pivot in intermediate mesh 90 with both of the other gears.

In testimony whereof I have affixed my signature in presence of two witnesses.

HERMANN DIEHL.
